DIRECTIONAL ATOMIZATION

Robert L. Menegus and Samuel J. Friedman, Wilmington, Del., and Frank A. Gluckert, West Chester, Pa., assignors to E. I. du Pont de Nemours & Company, Wilmington, Del., a corporation of Delaware

Application June 21, 1949, Serial No. 100,386

12 Claims. (Cl. 299—63)

1
This invention relates to a method and apparatus for the directional atomization of liquids, or liquids mixed with gases or vapors, or suspensions of solids in liquids, and is particularly directed toward securing a spray distribution which is restricted in cross section.

Control of spray distribution in the manner hereinafter described is highly desirable in chemical manufacturing processes wherein liquids, or solids in solution, or suspensions are spray-dried or spray-crystallized, or wherein intimate gas-liquid contacting must be effected to strip a more volatile component from less volatile carriers, or for other purposes. It has heretofore been the practice to conduct such operations in relatively large diameter chambers, for the reason that conventional atomizers produce a spray, part of which travels in a direction generally radial to the atomizer axis. This has been disadvantageous because large diameter chambers are expensive to construct, and even with a generous allowance in this respect, liquids or partially dried solids impinge on the wall surfaces where the materials remain largely outside of the zone of activity, or collect in deposits which hinder removal, or expose the product to the deleterious effects of overheating by prolonged hold-up in the heating zone.

An object of this invention is to provide a method and apparatus for atomizing liquids or slurries, either mixed or unmixed with gases or vapors, so that the spray distribution is substantially confined in pattern.

Another object of this invention is to provide a simple and economical apparatus for projecting liquids in an atomized state along a predetermined directional path.

Another object of this invention is to provide an apparatus for the atomization of liquids in medium or large sized drops substantially confined to a relatively narrow conical path.

Another object of this invention is to provide an apparatus for the atomization of liquids in such a manner that the atomized liquid possesses a relatively low velocity with respect to the atomizer chamber.

Other objects of this invention will become apparent upon consideration of this description together with the following drawings in which:

Figure 1 is a cross-sectional view of one embodiment of this invention taken along line 1—1 of Fig. 2.

Figure 2 is a bottom plan view of one embodiment of this invention provided with two liquid ejection cups, one of which is shown removed to more clearly illustrate the details of construction.

2
Figure 3 is a vertical sectional view of a liquid ejection cup.

Figure 4 is a sectional view taken along line 4—4 of Fig. 3.

5 Figure 5 is a partially diagrammatic representation of one embodiment of atomizing apparatus according to this invention shown in operation.

Figure 6 is a sectional view of a second embodiment of this invention taken along line 6—6 of Fig. 7.

Figure 7 is a bottom plan view of a second embodiment of this invention provided with two liquid ejection cups.

10 Figure 8 is a representation of a third embodiment shown in partial section along line 8—8 of Fig. 9.

Figure 9 is a bottom plan view of the third embodiment of this invention provided with two liquid ejection jets.

15 Figure 10 is a side view looking in the direction from the blade tip toward the supporting hub of Fig. 9.

Figure 11 is a sectional view taken on line 11—11 of Fig. 9.

20 In general, the objects of this invention are attained by imparting a rapid rotating motion to masses of liquid to be atomized (as in chamber 5) and then continuously ejecting the material through tangentially disposed jets inclined away from the direction of rotation, so that the radial force components are minimized and the liquid is projected away from the disperser in a direction substantially parallel to the axis of rotation. The radial force components are minimized by imparting to the material coming from the jets a velocity component parallel to the plane of rotation approximately equal and opposite to the velocity of the rapidly rotating tangentially disposed jets. This velocity is attained by impressing upon the liquid leaving the

25 jet a preselected pressure augmenting the pressure developed by the centrifugal field by methods described hereinafter, or by accelerating with or by means of a compressible fluid the liquid escaping from the jets. Under these conditions the liquid is atomized into drops having a distribution pattern which may be substantially circumscribed by a cylinder, or the pattern may be given various frusto-conical shapes by varying the velocity of ejection of the liquid from the dispersing jets in the manner hereinafter described.

30 Referring to Figs. 1 and 2, one embodiment of the atomizing head may comprise a disk 1 provided with a flanged peripheral edge 2 to which is fastened a closure plate 3 by means of circumferentially disposed screws 4 which engage tapped

35 50

55

Referring to Figs. 1 and 2, one embodiment of the atomizing head may comprise a disk 1 provided with a flanged peripheral edge 2 to which is fastened a closure plate 3 by means of circumferentially disposed screws 4 which engage tapped

holes in the edge of portion 2. The liquid chamber 5 thereby provided serves as a receiver and distributor of materials passing to the ejection jets. Chamber 5 is preferably divided into two compartments by two radially disposed vanes 6 which may conveniently comprise two lengths of angle iron of sufficient height to abut the inferior surfaces of disk 1 and plate 3. The purpose of vanes 6 is to minimize slippage between the liquid and the rotating disperser, vanes 6 extending from near the center of chamber 5 to the inside periphery of edge 2, thereby defining pockets for the reception of the feed liquid introduced through the hollow shaft 7 threadedly or otherwise suitable engaged to the hub portion of disk 1. To prevent disengagement of the atomizing head from its shaft, the screw threads may be cut in a direction reverse to the direction of rotation during operation, or relative movement between the head and the shaft elements may be prevented by pinning the parts together with suitable keys or set screws (not shown).

Plate 3 is provided with circular openings 8 which include shoulder portions 9 for the support of ejection cups 10. For purposes of simplicity in representation, the design of Figs. 1 and 2 has been limited to only two ejection cups; however, it will be understood that a greater number of these cups may be spaced apart evenly at a common radial distance from the center of disk 1, provided the angle of inclination of the liquid ejection passages, the speed of rotation, and the other operating conditions are controlled so that liquid atomized from one cup will not be impacted by the next succeeding cup in its rotational progress.

Cups 10 may be secured to disk 1 by through-going bolts 11 engaging with tapped holes in the interior of disk 1, the cups being drawn into liquid tight relationship abutting shoulders 9 and the bolts being sealed against leakage by gaskets 12.

Figs. 3 and 4 show one form of ejection cup which has proved highly effective for the atomization of liquid solely as distinguished from liquids admixed with gases or vapors. As shown, the cups are of generally cylindrical outside shape provided with a tapering internal bore 13, the sides of which are inclined at an angle up to about 60° to the vertical, or preferably so that the element of the cone through the axis of the liquid ejection passages 14 is perpendicular to said axis. In Figs. 3 and 4, the cups are provided with single cylindrical ejection passages 14. It is possible to operate with more than one ejection passage per cup provided that all of the passages are tangentially disposed to circles of equal radius and are located on the side of the cup away from the direction of rotation. Passages 14 are downwardly inclined at varying angles to the horizontal, depending on the conditions of operation, and the characteristics of the material which is to be atomized. The criterion for successful operation is that sufficient ejection pressure must be created by the combined centrifugal action and the impressed static pressure on the liquid entering the shaft so that the atomized liquid will take a path substantially in prolongation with the axis of head rotation, while at the same time preventing impacting of liquid discharged from any particular cup by the next succeeding cup. Satisfactory operation may be achieved with a downward inclination of passages 14 of from about 1½° to 60° referred to the horizontal. Clean cut ejection of liquid is facil-

tated by machining the area surrounding the outlet opening of passages 14 to a flat surface parallel to the tapered wall 13 at the point of ejection, as indicated at 15 in Fig. 4.

In the case where a gas or vapor is admixed with the liquid to accelerate its flow through the ejection cups to the requisite backward velocity, a modification of the cup design illustrated in Figs. 3 and 4 improves operation. The inside bores of cups handling both liquid and gas should be generally cylindrical with no taper, and the ejection passages disposed tangentially to the inner cylindrical bore. The ejection passages should be sufficiently long to permit thorough admixture of the gas with the liquid so that the expanding gas can accelerate the liquid to the necessary ejection velocity. In this connection, we have found a passage length to diameter ratio of from about 2 to 4 entirely satisfactory. When liquids and gases are to be ejected together, it will be understood that the ejection passages should be tangentially disposed to the path of atomizer rotation and located at the maximum radial distance from the axis of rotation. The passages should be aligned in the reverse sense to the direction of head rotation, in the same manner as hereinabove described for the liquid atomization application.

Referring to Fig. 5, a typical installation constructed according to the foregoing description comprises a hollow shaft 1 provided with a driving pulley 16 which is belt turned by a suitable driving motor (not shown). Shaft 1 is rotatably supported by bearings retained within a stuffing box of conventional design, indicated generally by reference numeral 17, which is mounted on the top wall 18 of the processing vessel. Liquid to be processed is supplied through pipe 21 under pressure from a suitable reservoir (not shown) through a rotating seal 20. If it is desired to use gas to accelerate the liquid projected from the ejection jets rather than relying on liquid supply pressure, the gas may be admixed with the liquid by forcing it under pressure into the liquid stream through pipe 19. Air admixture may also be accomplished by admitting air under pressure through a line opening at a point past the rotating seal 20 and within and concentric to shaft 1. With the exception of a substitution of ejection cups as hereinabove described, the design of Fig. 5 is suited to the atomization of either liquids, slurries, or liquids or slurries admixed with gases.

In operation, the feed liquid under pressure flows into the two compartments of chamber 5 defined by vanes 6 and is forced to the peripheral wall by the centrifugal field created by the rotation plus the shaft pressure. A high pressure is thereupon built up within cups 10 and liquid is ejected from passages 14. When the shaft pressure is adjusted to the correct value, the liquid is ejected at a velocity such that the component of this velocity in the plane of rotation is equal and opposite to the peripheral velocity of the cup. Under these conditions the liquid drops are not subject to radial forces upon ejection which tend to impel the drops outwardly to any substantial extent, and therefore their general course of travel is downward parallel to shaft 1. By varying the liquid delivery pressure in the shaft or the speed of rotation of the atomizing head, the discharge pattern may be altered from substantially cylindrical to a frustoconical envelope of an inclination of about 15° or more with the vertical, as indicated by the

schematic representation of the discharge pattern in Fig. 5. Since the spray pattern is restricted within controlled limits, it will be apparent that the atomized liquid may be efficiently contacted with gases within a relatively small diameter enclosure. In general, the side walls of the drier should be removed a distance of 3 or 4 atomizer diameters from the atomizer's vertical axis. Contacting gases, such as gases used for drying, may be introduced into the enclosure through suitable ports at either the top or bottom, and contacting may be effected in either co-current or counter-current relationship, as desired.

When gas is employed to accelerate the liquid to the requisite discharge velocity, liquid and gas flow simultaneously into the compartments of chamber 5, and the liquid is moved to the peripheral wall by the resultant forces. Liquid at high pressure therefore enters cups 10, and the gas passing under pressure through passages 14 accelerates the liquid's transit. By suitably adjusting the gas pressure, the component of velocity of the resultant spray in the plane of rotation away from the jets can be controlled to a degree where it is equal to the peripheral velocity of the cup by ejecting a liquid from a nozzle at the same velocity that the nozzle is moving in the opposite direction, a spray is produced that has substantially no movement radially from the atomizer. Thus, relative to a stationary observer, the liquid has no velocity. Where accelerating gas is employed, essentially the same spray pattern is obtained as when control is effected by variation of the liquid feed pressure; however, the drops so obtained will generally have a much smaller average size. Thus, with liquid-gas ejection the average drop size may be four or five times smaller than that obtained where no accelerating gas is used.

In a typical case, a two-cup atomizing head of 7" internal diameter was employed to disperse liquid by static pressure forces solely. The height of the internal chamber was $\frac{3}{8}$ " and the ejection cups had an internal height of 0.625" with a maximum diameter of 0.75" and a minimum diameter of 0.39". The ejection passages were 0.0313" in diameter with axes downwardly inclined to the horizontal at an angle of about 30°. The distance from the bottom of the internal conical cup to the center of the inner opening of the ejection passage was 0.125" measured along the vertical. This atomizer dispersed $\frac{1}{2}$ G. P. M. of water when rotated at a speed of 3520 R. P. M. with feed supplied to the shaft at room temperature and at a pressure of 35 lbs. per sq. in. gage.

In a typical case wherein gas was used to accelerate the liquid flow, an atomizing head of identical characteristics to that described in the preceding example, except with ejection passages 0.0625" in diameter and peripherally disposed, dispersed $\frac{1}{2}$ G. P. M. of water when rotated at 3500 R. P. M. with feed supplied at room temperature and air supplied at a pressure of 35 lbs. per sq. in. gage at a rate of 35 lbs. per hour.

When liquid pressure alone is used for the control of discharge velocity, there is, with a given ejection passage size, a given rate of rotation and a given distance of the nozzles from the axis of rotation, only one flow rate and one shaft pressure which corresponds to the condition where the liquid is accelerated at a velocity precisely equal and opposite to that of the rotating cups. Thus, to adjust for changes in flow

rate, it is necessary to either change the size of the ejection passage or to change the rate of rotation. Where gas is used to accelerate the liquid to the requisite velocity, it is possible to vary the discharge rate of liquid from the jets without changing the rate of rotation merely by adjusting the gas flow rate and pressure to a suitable value. In order to obtain equal discharge rates at the same rotational speeds of operation, the jets of the liquid-gas atomizer should be somewhat larger in diameter than where liquid under pressure is relied on for velocity control.

Figs. 6 and 7 illustrate the construction of a second embodiment of this invention which is intended to disperse liquids and slurries only, as distinguished from liquids or slurries admixed with gas. This design incorporates a pumping element as an integral feature of the atomizing head, elements similar to those hereinabove described being designated by the same reference numerals. Referring to Fig. 6, hollow shaft 7 constitutes the passage for introduction of liquid feed into the atomizing head, shaft 7 being independently rotated by a drive pulley 16 such as that shown in Fig. 5. Shaft 7 is guided by upper and lower bearing sets 30 which are retained in place by supporting collars 31. The upper collar 31 is fixedly secured to outer casing 28 by means of key 22, while lower support 31 is pinned to 28 by recessed set screws, such as 23. The annular space between shaft 7 and casing 28 may be utilized as a lubricant reservoir for bearings 30, the open end being closed against the entrance of dust and other foreign materials by closure plate 42 fixedly attached to gear portion 35 by screws 43.

Shaft 7 is closed at its bottom end to which is fastened the four-bladed pump impeller 25 by means of set screw 24 and key 26. The lower end of shaft 7 is provided with four holes 27 spaced 90° apart for the passage of liquid into the spaces between the impeller blades. The diameter of holes 27 is preferably about four times the diameter of ejection passages 14 to avoid clogging troubles, particularly when slurries are being processed, and to insure an ample supply of feed to the ejection cups. The interior space between shaft 7 and casing 28 is sealed against leakage from the liquid chamber 5 by packing 29 which is retained in place by an annular metal plate 32 secured to lower collar 31 by screws such as that indicated at 33. The clearance between impeller 25 and the walls of chamber 5 is not critical so long as an efficient pumping action is attained, the clearances preserved in conventional pump manufacture being entirely satisfactory.

In the embodiment of Figs. 6 and 7, disk 1 is provided with a thickened hub portion 34 which is internally threaded for engagement with the lower end of casing 28. Casing 28 is provided with an integral toothed gear portion 35 at its upper end which engages with gear 36 driven from a suitable power source not shown. Casing 28 is guided in external bearings 37 which are retained in place by housing 38 bolted to wall 18 of the enclosure. The bearings are protected against the entrance of foreign material by closure plate 40 secured to housing 38 by screws 41. Annular space 39 provides a channel for the circulation of lubricant to the bearings, and leakage into the enclosure space may be prevented by suitable packing glands, not shown, closing off the space where casing 28 enters wall 18.

In operation, it will be understood that im-

Impeller 25 and the atomizing head or disk 1 both rotate in the same direction but at different speeds. Ejection cups 19 are identical with those previously described with their openings oriented in a direction opposite to that of rotation and with their axes tangent to a circle drawn from the center of shaft 7. A two-cup atomizing head of this design, having a chamber of 9" internal diameter and an internal height of $\frac{3}{8}$ ", provides sufficient space for the installation of a 7" diameter four-blade impeller. A device of these characteristics will deliver about 2.78 G. P. M. of water when the atomizing head is rotated at 3600 R. P. M. and the impeller is rotated in the same direction at 6200 R. P. M., the ejection passages being 0.0625" diameter downwardly inclined to the horizontal at an angle of about 30°.

A third embodiment of this invention which is effective for the atomization of liquids or slurries alone or in admixture with gas or vapor, is disclosed in Figs. 8, 9, 10 and 11. This design is somewhat preferred over that of Figs. 1 and 2 for the reason that the large expanse of flat surface comprising the outer face of plate 3 (refer Fig. 1) is eliminated and there is a minimum of backward drag on the drops causing troublesome redeposition on the atomizing head. Where relatively narrow blades are employed the angle of inclination of the ejection passages may be reduced to as low as 5° or less, resulting in improved dispersion at a very low downward velocity. A second advantage is that the blades are individually adjustable so that the angle of inclination of the ejection passages may be varied at will to suit the requirements of the materials being processed.

Referring to Fig. 8, hollow rotating shaft 7 is reduced at the lower end for the threaded reception of atomizing head 44 which may be locked in place by conventional keys or set screws, not shown. Opposite sides of head 44 are machined flat as shown in Fig. 9 to receive blade bases 45, only two of which are shown although a greater number may be added. Blade elements 46 may be detachably supported in bases 45 but are preferably welded thereto as shown. Bases 45 are provided with arcuate slots 52 disposed at equal angular distances for the reception of socket head bolts 47. The inner faces of bases 45 are provided with circular raised keys 53 which mate with companion circular slots in head 44. The angles of inclination of the blades 46 and their associated ejection passages are readily adjusted by loosening the three bolts 47, whereupon bases 45 may be turned to the desired position and again locked in place by tightening the bolts.

A further advantage of this embodiment of our invention therefore is that with these impeller blades projecting in the same direction as the direction of the atomization, the drying is projected along the same course as the process material and prevents or eliminates deposition on the atomizer housing of the material being processed.

In operation, liquid is supplied to blades 46 through radial passages 48 which open into offset passages 49 in the body portions. The angle of offset of passages 49 is such that the outlet openings of the ejection passages will be tangent to a circle drawn from the center of head 44 at any inclination to which the blades are adjusted. For ease in fabrication and cleaning, the outer ends of passages 49 are closed with imperforate screw plugs 54. Short passages 50, coaxial with the ejection passages, divert the liquid to the dis-

charge openings. As shown in Fig. 11, blades 46 resemble air foils in cross section, the trailing edge being tapped to receive socketed jet plugs 51 which are centrally drilled to the ejection passage size desired. Plugs 51 recess within tapped passage 50 a sufficient amount so that firm engagement therewith is had, retention being improved by small set screws if necessary. For best results, the outer openings of the jet passages of opposite blades should lie on a common line drawn through the center of head 44. The enlarged openings in the trailing edges surrounding the ejection passages do not interfere with the atomization of drops from the blade ends.

This invention is applicable to the dispersion of liquids, mixed liquids, slurries, colloidal solutions, or any of the foregoing admixed with gases, and it is intended that the phrase "substances having a liquid continuous phase" used herein and in the claims shall be construed as broadly inclusive of all of these systems.

It will be understood also that many modifications and variations may be made within the scope of our disclosed invention without departing from its essential principles, and we intend to be limited only to the extent indicated in the appended patent claims.

We claim:

30. 1. The method of atomizing substances having a liquid continuous phase to produce a spray pattern substantially confined in cross section comprising developing centrifugal forces in successive increments of said substances while maintaining said substances under a static pressure head, projecting said substances tangentially in a direction opposite to the direction of rotation at a velocity substantially equal and opposite to the velocity component in the plane of rotation, and dispersing said substances as discrete drops in a direction substantially opposite to the instant direction of rotation and downwardly at an angle of between about 1½° and 60° measured from the horizontal.
45. 2. The method of atomizing substances having a liquid continuous phase in order to procure a spray pattern substantially confined in cross section comprising injecting a gas under pressure into a continuously flowing stream of said substances, developing centrifugal forces in succeeding increments of said substances, projecting said substances tangentially in a direction opposite to the direction of rotation at a velocity substantially equal and opposite to the velocity component in the plane of rotation, and dispersing said substances as discrete drops in a direction substantially opposite to the instant direction of rotation and downwardly at an angle of between about 1½° and 60° measured from the horizontal.
60. 3. Apparatus for the atomization of substances having a continuous liquid phase comprising a rotatable shaft, a hollow casing secured thereto, means for the supply of feed material to said casing, ejection passages located near the periphery of said casing with their axes lying in planes tangent to a circle drawn about the axis of said shaft as a center, said ejection passages being inclined downwardly at an angle between about 1½° and 60° measured from the horizontal with discharge openings oriented in a direction opposite to that of rotation.
75. 4. Apparatus for the atomization of substances having a continuous liquid phase comprising a rotatable shaft, a hollow casing affixed there-

to, means for the supply of feed material to said casing, means for injecting gas under pressure into the feed material flowing into said casing, ejection passages located near the periphery of said casing with their axes lying in planes tangent to a circle drawn about the axis of said shaft as a center, said ejection passages being inclined downwardly at an angle between about $1\frac{1}{2}^{\circ}$ and 60° measured from the horizontal with discharge openings oriented in a direction opposite to that of rotation.

5. The apparatus of claim 4 including means for serving each of said ejection passages comprising a separate feed receiving pocket defined by radial vanes affixed to the interior of said casing and extending from near the center of the casing to the inside peripheral edge thereof.

6. Apparatus for the atomization of substances having a continuous liquid phase comprising a hollow rotatable shaft, a hollow casing affixed thereto, a second rotatable shaft of smaller diameter than said first shaft and concentrically disposed within said first shaft, said second shaft having a centrifugal pump impeller disposed within the interior of said casing, means for rotating said shafts in the same direction but driving said first shaft at a substantially lower speed than said second shaft, means for supplying feed material to said casing, ejection passages located near the periphery of said casing with their axes lying in planes tangent to a circle drawn about the common axis of said shafts as center, said ejection passages being inclined downwardly at an angle between about $1\frac{1}{2}^{\circ}$ and 60° measured from the horizontal with discharge openings oriented in a direction opposite to that of rotation.

7. Apparatus for the atomization of substances having a continuous liquid phase comprising a hollow rotatable shaft provided at its lower end with a closing head fixedly attached thereto, at least two hollow, oppositely aligned, radially disposed blades mounted on said head in open communication with the interior of said shaft, the outer ends of said blades having ejection passages with axes lying in planes tangent to a circle drawn about the axis of said shaft as a center, with said ejection passages inclined downwardly at an angle between about $1\frac{1}{2}^{\circ}$ and 60° measured from the horizontal and having discharge openings oriented in a direction opposite to that of rotation.

8. The apparatus of claim 7 in which said blades are separable from said head and the inner ends of said blades are provided with arcuate slots for the reception of means for securing said blades to said head, and for adjusting the inclination of said blades.

9. Apparatus for the atomization of substances having a continuous liquid phase comprising a rotatable shaft for supplying liquid under pressure, a hollow casing or chamber affixed thereto for receiving and distributing the liquid in a horizontal plane, means for channeling the liquid from the receiving chamber, means for injecting gas under pressure into the feed material flowing into said casing, and through said chamber, ejection passages located at the termination of said channels with their axes lying in planes tangent to a circle drawn about the axis of said shaft as a center, said ejection passages being inclined downwardly at an angle between about $1\frac{1}{2}^{\circ}$ and 60° measured from the horizontal with their discharge open-

ings oriented in a direction opposite to that of rotation.

10. Apparatus for the atomization of substances having a continuous liquid phase comprising a rotatable shaft, a hollow casing secured thereto, rotating means for the supply of feed material to said casing, means for reducing slippage between the liquid and the rotating means, ejection passages located near the periphery of said casing with their axes lying in planes tangent to a circle drawn about the axis of said shaft as a center, said ejection passages being inclined downwardly at an angle between about $1\frac{1}{2}^{\circ}$ and 60° measured from the horizontal with discharge openings oriented in a direction opposite to that of rotation.

11. Apparatus for atomization of substances having a continuous liquid phase, comprising a hollow, vertically positioned, rotatable shaft, a hollow casing secured thereto and forming a generally cylindrical, horizontally positioned chamber for receiving and distributing outwardly therefrom materials supplied through said rotatable shaft, a multiplicity of ejection passages arranged in spaced relation to each other and from the intake to said cylindrical chamber and inclined downwardly at an angle of between about $1\frac{1}{2}^{\circ}$ and 60° measured from the horizontal to eliminate interception of the spray from one by the next succeeding spray, at various speeds of rotation, radially and horizontally disposed distributing channels for supplying the liquid substances from said cylindrical chamber to said ejection passages, and downwardly inclined passage-ways connecting said channels with said downwardly inclined ejection passages.

12. Apparatus for the atomization of substances having a continuous liquid phase comprising a rotatable shaft, a receiving chamber secured thereto, means for the supply of feed material to said chamber, downwardly inclined ejection passages located near the periphery of said casing with their axes lying in planes tangent to a circle drawn about the axis of said shaft as a center, means for reducing the slippage between the liquid from the feed supply to the ejection passages comprising vanes extending horizontally from near the center of the receiving chamber casing to control the flow of liquid to the nozzles, said downwardly inclined, ejection passages having their discharge openings oriented in a direction opposite to that of rotation, and in spaced relation to eliminate interception of the spray from one by the next succeeding spray.
